(57) **CLAIM**

The ornamental design for a Christmas tree light, as shown and described.

DESCRIPTION

FIG. 1 is a perspective view of a Christmas tree light showing my new design.

FIG. 2 is a front view thereof.

FIG. 3 is a rear view thereof.

FIG. 4 is a left side view thereof.

FIG. 5 is a right side view thereof.

FIG. 6 is a top view thereof.

FIG. 7 is a bottom view thereof.

FIG. 8 is a bottom perspective view thereof; and,

FIG. 9 is an enlarged detail view of area 9 shown in FIG. 1. The broken lines in the drawings depict portions of the Christmas tree light that form no part of the claimed design. The labeled broken line portion shown in FIG. 1 and the broken lines shown in FIG. 9 are for the purpose of illustrating the boundaries of the enlarged fragment and form no part of the claimed design.

1 Claim, 9 Drawing Sheets
